(57) **CLAIM**

The ornamental design for a motor vehicle body, toy vehicle body replica and/or other replica as shown and described.

DESCRIPTION

FIG. 1 is a top, front, and right side perspective view of a motor vehicle body, toy vehicle body replica and/or other replica showing my new design;

FIG. 2 is a front view thereof;

FIG. 3 is a rear view thereof;

FIG. 4 is a right side view thereof, the left side being a mirror image thereof; and,

FIG. 5 is a top view thereof.

The broken lines in the drawings illustrate portions of the motor vehicle body, toy vehicle body replica and/or other replica that form no part of the claimed design.
